UNITED STATES PATENT OFFICE.

EDSON O. SESSIONS, OF CHICAGO, ILLINOIS.

LOCKING-SWITCH.

1,310,168.

Specification of Letters Patent. Patented July 15, 1919.

Application filed September 6, 1917. Serial No. 189,922.

To all whom it may concern:

Be it known that I, EDSON O. SESSIONS, a citizen of the United States, residing at Chicago, in the county of Cook and State of Illinois, have invented a certain new and useful Improvement in Locking-Switches, of which the following is a specification.

My invention relates to an improved construction of locking switch for use in narrow passageways requiring practically vertical motion of the operating tool to actuate the locking mechanism and open the switch. It is now common practice in the art to require electrical switches to be equipped with positive locking devices where the switches are employed in connection with alternating current circuits of high tension and high amperage as for example in generating stations and it is frequently necessary to mount switches of this kind on a wall or switchboard at a considerable height above the floor in locations where a wall of the building or a partition is so near the switch as to afford only sufficient room for the opening thereof. In such cases the operator must stand nearly below the switch device and the operating tool used to open and close the switch can assume no other than practically a vertical position, it being impossible under such conditions to stand at a distance sidewise from the switch to exert force in a lateral direction to move the free end thereof in opening and closing the switch. My invention provides a construction of locking mechanism adapted for use under such conditions characterized by securing a bracket or housing to the switch blade at or near its free end, which bracket or housing is offset sufficiently from the switch blade so that when an operating tool is inserted through openings formed in the housing to receive it and a thrust is exerted on the operating tool substantially parallel with the switch blade in its closed position, a lateral component of said thrust is exerted on the switch sufficient to readily open the same. Furthermore the locking devices employed and the openings in the housing are so conformed that said thrust on the operating tool positively operates the locking mechanism to release the switch blade. Similarly when the switch is being closed the construction referred to results in imparting to the housing and switch blade sufficient lateral force for an upward motion of the operating tool in a nearly vertical

direction, to positively close the switch and engage the locking mechanism so as to positively hold the switch in its closed position.

My invention will best be understood by reference to the accompanying drawings showing a preferred embodiment thereof, in which—

Figure 1 shows one of my improved switching mechanisms in side elevation 65 mounted for use,

Fig. 2 is a front elevation of the switching mechanism shown in Fig. 1,

Fig. 3 is a detail sectional view of the locking mechanism employed in connection 70 with the switching mechanism shown in Figs. 1 and 2, and

Fig. 4 shows a detailed view of an operating tool for use with the switching mechanism. 75

Similar numerals refer to similar parts throughout the several views.

As shown in Fig. 1 the switching mechanism consists of a metal base 10 which carries a clamp at either end for supporting 80 the insulators 11 and 12. The base is provided with clamps for engaging rods or pipes 13 and 14 to support the switching mechanism. The insulator 12 has rigidly secured to its outer end a pivot clip 15 and the insulator 11 has rigidly secured to its outer end a contact clip 16. The pivot clip 15 has pivotally secured thereto a switch blade 17, the pivot and contact clips being so disposed upon their insulators that the 90 switch blade properly engages the contact clip when the switch is closed. The switch blade carries at or near its free end a lock housing 18 from which a locking latch 19 projects to engage a catch 20 mounted adjacent the contact clip 16, said engagement serving to hold the switch blade positively in its closed position. 95

As shown in Fig. 3 the latch 19 is pivotally supported in the housing 18 at 21 100 and has rigidly secured thereto an operating lever 22 extending to the left hand in said housing and overlapping the openings 23 formed through the housing to receive an operating tool, which may be of the construction shown in Fig. 4 consisting of an insulating handle 24 which carries at its upper end a bent metal rod 25 having at its upper end an enlarged pointed head 26 facilitating inserting the tool through the 110 openings 23.

It will be observed that the housing 18 is

considerably offset from the center line of the switch blade 17 and that the openings 23 are disposed wholly to the left of said center line as seen in Figs. 1 and 3, said openings extending upwardly to the right and downwardly to the left at an angle of substantially 45 degrees to said center line. A compression spring 27 is disposed between the latch 19 and a web in the housing 10 which tends to hold said latch in its locking position.

The purpose of the offset construction referred to is as follows:

When the switching mechanism is mounted in locations for which it is particularly designed, as for example in narrow passageways a wall or partition 28 of the building may be near enough the switching mechanism so as to provide only sufficient clearance for moving the switch blade 17 to its open position. Under these conditions an operator standing on the floor 29 finds it impossible to place the operating tool 24 in any other than a nearly vertical position when engaging the openings 23 to operate the locking mechanism and open the switch. The inclined sides of the openings 23 referred to direct the bent end 25 of the operating tool downwardly to the left into engagement with the lever 22 of the locking mechanism for which condition a downward pull on the operating tool moves the latch 19 to its releasing position. The offset construction of the housing 18 results in separating the operating tool 24 some distance laterally from the switch blade 17 thus exerting upon the upper end of the switch blade a corresponding lateral thrust when the downward thrust on the operating tool is continued, this lateral component being sufficient to move the switch blade 17 from engagement with the contact clip 16. Under the conditions described it is practically impossible for the operator to exert other than a substantial vertical pull in a downward direction upon the housing 18 and were the housing not offset as described the releasing of the locking mechanism could hardly be effected and it would be practically impossible particularly with switches of considerable size to exert a sufficient lateral thrust on the free end of the switch blade to open the switch. It will, of course, be understood that the amount of the offset of the housing 18 from the center line of the switch blade is determined by the amount of lateral force required to open and close the switch and that I do not limit myself to any particular amount of offset. In closing the switch an upward thrust on the operating tool in a nearly vertical direction produces an upward thrust on the web 30 formed across the upper end of the openings 23, which thrust as a result of the lateral displacement of the operating tool from the switch

blade due to the offset referred to, exerts a sufficient lateral thrust on the free end of the switch blade to positively move the switch blade into engagement with the contact clip and bring the latch 19 into locking engagement with the catch 20.

While I have shown my invention in the particular embodiment above described it will be understood that I do not limit myself to this exact construction, as I may employ equivalents thereof known to the art at the time of the filing of this application, without departing from the scope of the appended claims.

What I claim is:

1. In a locking switch, the combination of a pivot clip, a contact clip, a switch blade pivotally connected to said pivot clip and engaging said contact clip when the switch is closed, a housing carried by the end of said switch blade and projecting laterally from the outer edge of the switch blade, a latch contained in said housing and pivotally mounted therein, said latch having a hook projecting from the inner edge of said housing, said housing having oblique openings through its opposite walls for receiving an operating tool, a fixed catch for engaging said hook when the switch blade is closed, and a lever contained in said housing for operating said latch, said lever overlapping said openings to be engaged and operated by said tool.

2. In a locking switch, the combination of a pivot clip, a contact clip, a switch blade pivotally connected with the pivot clip and engaging the contact clip when the switch is closed, a bracket carried by the switch blade, said bracket having an offset portion projecting beyond one edge of the switch blade, said bracket having an opening in said offset portion for receiving an operating tool, the edge of said opening engaged by said tool being oblique to the axis of the switch blade, a latch pivoted to said bracket and having an extension overlapping said opening, and a catch for engaging said latch when the switch is closed, whereby the operating tool is displaced laterally from the switch blade in the direction of the opening movement to produce a lateral thrust on the switch blade when the operator is beneath said switch and said switch is vertically disposed.

3. In a locking switch, the combination of a pivot clip, a contact clip, a switch blade pivotally connected with the pivot clip and engaging the contact clip when the switch is closed, a bracket carried by the switch blade, said bracket having an offset portion projecting beyond one edge of the switch blade, said bracket having an opening in said offset portion for receiving an operating tool, the edge of said opening engaged by said tool being oblique to the axis of the switch blade,

and mechanism for locking said switch in its closed position, said locking mechanism overlapping the opening in said bracket, whereby a pull on the operating tool when in said opening and substantially parallel with said switch blade releases said locking mechanism and produces a lateral thrust on said switch blade. 25

5. In a locking switch, the combination of 10 a pivot clip, a contact clip, a switch blade pivotally connected with the pivot clip and engaging the contact clip when the switch is closed, a bracket carried by the switch blade, said bracket having an offset portion 30 projecting beyond one edge of the switch blade, said bracket having an opening in said offset portion for receiving an operating tool, and mechanism for locking said switch in its closed position, said locking mechanism overlapping the opening in said bracket, whereby a pull on the operating tool when 35 in said opening and substantially parallel with said switch blade releases said locking mechanism and produces a lateral thrust on said switch blade. 40
4. In a locking switch, the combination of 15 a pivot clip, a contact clip, a switch blade pivotally connected with the pivot clip and engaging the contact clip when the switch is closed, a bracket carried by the switch blade, said bracket having an offset portion 45 projecting beyond one edge of the switch blade, said bracket having an opening in said offset portion for receiving an operating tool, a latch pivoted to said bracket and having an extension overlapping said opening, and a catch for engaging said latch when the switch is closed, whereby the operating tool is displaced laterally from the switch blade in the direction of its opening movement to produce a lateral thrust on the switch blade 20

when the operator is beneath said switch and said switch is vertically disposed. 25

5. In a locking switch, the combination of a pivot clip, a contact clip, a switch blade pivotally connected with the pivot clip and engaging the contact clip when the switch is closed, a bracket carried by the switch blade, said bracket having an offset portion projecting beyond one edge of the switch blade, said bracket having an opening in said offset portion for receiving an operating tool, and 35 mechanism for locking said switch in its closed position, said locking mechanism overlapping the opening in said bracket, whereby a pull on the operating tool when 40 in said opening and substantially parallel with said switch blade releases said locking mechanism and produces a lateral thrust on said switch blade. 45

In witness whereof, I hereunto subscribe my name this twenty-fifth day of August, 45
A. D. 1917.

EDSON O. SESSIONS.
